UNITED STATES PATENT OFFICE

JOHN H. ANDERSON, OF DETROIT, MICHIGAN, ASSIGNOR TO ALTITHERMO ENGINEERING COMPANY, A CORPORATION OF PENNSYLVANIA

APPARATUS FOR CRACKING AND DISTILLING HYDROCARBONS

Application filed October 8, 1928. Serial No. 310,951.

The present application is in part a continuation of an application for Letters Patent filed by me on March 10th, 1928, Serial Number 260,576, and the present invention resides in improved apparatus for cracking and distilling hydrocarbons, both liquid and solid, of the type wherein the operation is carried on in an externally heated revolving retort or hollow drum, containing a loose mass of heat-conducting metal bodies, the charge being introduced at one end of the retort and the products of the operation being withdrawn or discharged at or near the opposite end, while the substances being heated within the retort are agitated, broken up, and eventually (if the operation is sufficiently extended) comminuted or pulverized, by the tumbling about of the loose mass of metal bodies. By the use of the improved apparatus maximum quantities of the desired products are obtained economically and effectively, in a continuous operation, while all, or substantially all, of the residue, in granular or pulverulent condition, may be automatically discharged, without undesirable accumulation of residue within the retort, and the latter is thereby made self-cleaning. I have so used the apparatus with marked success in the production of fixed gas of high heat value from coal tar and heavy liquid hydrocarbons. It can be used with like advantage in the obtainment of light liquid products from heavier liquids, and in the distillation of coal, shale and other solid carbonaceous substances as well.

In the accompanying drawings Figure 1 is a central sectional elevation of apparatus embodying the invention, shown as utilized primarily for the obtainment of fixed gas from coal tar or other heavy liquid hydrocarbons. Figure 2 is a front end elevation omitting the supply tank. Figure 3 is an axial sectional plan view of the conical drum or retort. Figure 4 is a side elevation of the central one of three rings which constitute a lower thrust-bearing for the retort. Figure 5 is a sectional elevation of said three bearing rings assembled. Figure 6 is a fragmentary sectional elevation showing the front portion of the structure of Figure 1

as modified for the use of the apparatus for the distillation of coal or other solid substance.

Referring to Figures 1 and 2 of the drawings, the necessary heat is generated in the combustion chamber 1 of the furnace 2 by means of burners 3 projecting through the front wall 4, and the products of combustion pass out through the stack 5 opening out of the combustion chamber. Rotatably supported in the combustion chamber by means to be described presently is the hollow retort 6, which is preferably a metallic shell, and is of the contour of a truncated cone, having at its smaller rear end a coaxial tubular throat 7, which projects out through the rear wall of the combustion chamber, and the open end of which is closed by a perforated screen or lattice 8. The conical retort 6 is tilted over on its side and is supported within the combustion chamber with the lowermost longitudinal line of its side wall in horizontal position, or substantially so, as shown in Figure 1, and consequently with its axis downwardly inclined from front to rear. In the front wall 9 of the larger end of the retort 6, which is adjacent to the front wall 4 of the combustion chamber, there is formed an axial tubular throat 10, which projects outwardly through an opening in said front wall and to which is connected the tubular hub 11 rotatably mounted in bearings 12 formed or mounted in the heavy metal frame 13 back of the furnace. Formed upon or secured to the hub 11 is the worm-wheel 14, which meshes with the worm 15 on the shaft 16 of the motor 17. Outside the rear wall of the furnace the downwardly inclined tubular extension 7 of the retort rests upon correspondingly inclined bearing rollers 18, and its outer screened open end projects through the inclined lateral opening 19 in the T 20, which has also the upwardly projecting delivery pipe 21 for the gaseous products coming from the retort, and the downwardly projecting discharge pipe 22 for the granular and more or less pulverulent residue. An external annular shoulder 23 is formed on the extension 7, and a cooperating internal 100

shoulder 24 on the thickened wall or head 25 surrounding the opening 19, and between these shoulders are arranged the bearing rings or annular discs 26, 27, 28, the ring 26 being pinned to the shoulder 23, and the ring 28 pinned to the shoulder 24, with the ring 27 confined between them, as shown in Figure 5. The ring 27 has oil pockets 29 formed in its opposite faces, as shown in Figure 4, and lubricating oil is supplied to the bearing from the oil-cup 30 shown in Figure 1. A very effective thrust-bearing is thus provided for the rear or discharge end of the retort, and one which is practically 10 impervious to the passage of gas or air. A water-channel 31 is formed in the annular head 25, having a water-inlet pipe 32 and an outlet-pipe 33, as also shown in Figure 1. At the opposite end of the apparatus the 20 outer end of the tubular hub 11 is tightly closed by a stuffing-box 34, through which passes the oil-supply pipe 35, which leads from the oil-tank 36 through the hub 11, and opens into the front of the retort 6. A cock 37 is provided in the pipe 35 for controlling the flow of the oil therethrough.

The mass 38 of loose metal bodies is shown in Figures 1 and 3 of the drawings. When the retort 6 is at rest the surface of this 30 mass forms a substantially level floor extending from the front of the retort to the screen 8, by which it is confined at the rear. When in this condition also the mass within the conical body of the retort is of even 35 depth on its central longitudinal line, by reason of the fact that the lowermost line of the bottom wall of the retort is horizontal, or, as it may be said, the retort is supported upon an even keel; but by reason of the conical form of the retort, both the width of the 40 mass and its cross-sectional area gradually increase from rear to front, the greater volume of the mass being at the front of the retort in the locality of the points of supply 45 of the oil or other substance to be treated. The employment of a mass of loose metal bodies in an externally heated rotating retort is not broadly new with me, but such employment in an externally heated retort 50 of the form herein shown and described is believed to be new, and it has been found to possess great advantages over other apparatus previously proposed to be used for similar purposes. For example, if a cylindrical horizontally supported retort be used, the dimensions and volume of the loose mass 55 will be uniform throughout its length, while if the retort or the floor of the retort be materially inclined, the mass will be the sparser at the inlet end where its volume 60 should be the greatest. The mass of metal bodies in being tumbled about during the rotation of the retort not only agitate and break up the oil under treatment, but having 65 themselves become highly heated during the

operation, they impart their accumulated heat to the charge. I have found it to be of great advantage, not only with respect to speed of operation and quantity of product, but with respect to quality of product as well, to supply the oil to the retort at a rate approximating its maximum working capacity, and to effectively operate upon the successive increments of the supply immediately upon their introduction into the retort, and consequently the operation is greatly improved by the maintenance of a relatively large area and volume of the loose metal bodies at and in the immediate neighborhood of the region of initial supply. 70

The individual metal bodies composing the loose mass may be of a variety of forms. They may be spherical balls, or egg-shaped, cylindrical or polyhedral; or they may be irregular, broken chunks of metal; or the 80 mass may include bodies of several different shapes. The bodies may be iron or steel; or, if desired, they, or some of them, may be of metal having a catalytic effect, such as nickel. In tumbling about within the retort 85 the metal bodies continually agitate, stir and break up the tarry matter and other residue as it forms, until under combined heating and attrition the residue ultimately becomes dry and granular or pulverulent. The openings through the screen or lattice are of such size that the metal bodies will be retained in the retort, while the granular residue will flow out freely and automatically into and through the discharge-pipe or other outlet 90 95 100. The metal bodies keep one another clean, and they also keep the inner surface of the retort clean and free from any accumulation of residue, so that the heat will be conducted freely and uniformly through the wall of the retort. Therefore the operation will proceed continuously and automatically under the best conditions. 105

By reason of the conical form of the retort and the inclined position of its axis, with the lowermost longitudinal line of its wall substantially horizontal, the retort as a whole imposes pressure upon its rear bearing between the shoulders 23 and 24, thus making a thrust-bearing which can be effectively 110 sealed by the means described, or by equivalent means, against leakage of either gas or air through the joint. This is a matter of great importance. If the operation within the retort is being conducted under super-atmospheric pressure, passage of the gases out through this joint may easily create a very dangerous environment. While if the operation is being conducted under a small vacuum the consequences of drawing air inwardly into the flowing gaseous stream may well be equally harmful. An important factor in the maintenance of a tight joint is the relatively small diameter of the outlet end of the retort and of the extension 7 as compared 115 120 125 130

with that of the body of the retort, whereby the thrusting stress of the retort upon this bearing at the discharge end is greatly augmented. And the effective cooling of this bearing is also an important factor in the maintenance of a tight joint at all times.

It will of course be understood that if the substance to be treated is a very viscous oil, tar or pitch, suitable means, such as a closed steam coil in the tank 36, and a steam jacket around the pipe 35, will be provided in order to render and maintain it sufficiently fluid to flow freely.

In Figure 6 of the drawings I have shown the front or inlet end of the retort equipped with means for supplying a broken or granular solid substance, such as coal or oil shale. The hopper 40 opens into a tubular throat 41, which is suitably supported in registry with the outer open end of the tubular throat 10 of the retort, and a screw-conveyor 42, having a driving wheel 43 at its outer end is arranged in said aligned throats, and serves to transport the substance into the retort. The 25 operation will then proceed substantially as hereinbefore described.

I claim as my invention:

1. An apparatus for cracking and distilling solid or liquid hydrocarbons comprising, in combination, a heating-chamber and means for supplying heat thereto, a conical retort rotatably supported within the heating-chamber with its axis inclined downwardly from its larger to its smaller end, 35 with the lowermost longitudinal line of its conical wall in substantially horizontal position, an inlet for the supply of the substance to be heated into the larger end of the retort, a loose mass of metal bodies contained within the retort, an outlet at the smaller end of the retort, a screen in the outlet permitting the discharge of the products of the operation but retaining said metal bodies within the retort, and means for axially rotating the retort.

2. An apparatus for cracking and distilling solid or liquid hydrocarbons comprising, in combination, a heating-chamber and means for supplying heat thereto, a conical metallic retort having a smooth and unobstructed inner surface rotatably supported within the heating-chamber with its axis inclined downwardly from its larger to its smaller end and with the lowermost longitudinal line of its conical wall in substantially horizontal position, hollow inclined axial trunnions opening out of the retort at its opposite ends and projecting through the opposite end walls of the heating-chamber, 50 means connected to the trunnion at the larger end of the retort for supplying the substance to be treated, a receiver for the products of the operation connected to the opposite trunnion, a bed of loose metal bodies extending 55 from end to end within the retort, a screen

in the said opposite trunnion preventing the discharge of said metal bodies but permitting the free flow of the products of the operation, and means connected to one of the trunnions for rotating the retort.

3. An apparatus for cracking and distilling solid or liquid hydrocarbons comprising, in combination, a heating-chamber and means for supplying heat thereto, a conical retort rotatably supported within the heating-chamber with its axis inclined downwardly from its larger to its smaller end, 70 hollow inclined axial trunnions opening out of the retort at its opposite ends and projecting through the opposite end walls of the heating-chamber, means connected to the trunnion at the larger end for rotating the retort, an annular bearing-shoulder on the opposite trunnion, a receiver for the products of the operation having a cooperating shoulder, and a thin ring loosely confined between said shoulders.

4. An apparatus for cracking and distilling solid or liquid hydrocarbons comprising, in combination, a heating-chamber and means for supplying heat thereto, a conical retort rotatably supported within the heating-chamber with its axis inclined downwardly from its larger to its smaller end, 75 hollow inclined axial trunnions opening out of the retort at its opposite ends and projecting through the opposite end walls of the heating-chamber, means connected to the trunnion at the larger end for rotating the retort, an annular bearing-shoulder on the opposite trunnion, a receiver for the products of the operation having a cooperating shoulder, a thin ring loosely confined between said shoulders having oil pockets formed in its opposite faces, and means for supplying 80 lubricating oil to the bearing.

In testimony whereof I have hereunto set my hand.

JOHN H. ANDERSON.
